UNITED STATES PATENT OFFICE.

WILLIAM S. McBRIDE, OF CALDWELL, OHIO.

DRILLING DEVICE.

1,424,109.

Specification of Letters Patent. Patented July 25, 1922.

Application filed February 7, 1921. Serial No. 443,115.

To all whom it may concern:

Be it known that I, WILLIAM S. McBRIDE, a citizen of the United States, residing at Caldwell, in the county of Noble and State 5 of Ohio, have invented new and useful Improvements in Drilling Devices, of which the following is a specification.

This invention relates to well drilling apparatus, particularly for use in connection 10 with oil wells, and has for its object the provision of means for drilling horizontally at any desired point along a well for any purpose desired.

An important and more specific object is 15 the provision of a drilling device which may be lowered into a previously drilled well and which includes a bit member being carried by a flexible shaft device rotatable to effect rotation of the bit member and the carrier 20 for the device being rotatable within the well whereby a cut of a complete circle may be formed if desired.

An additional object is the provision of 25 a device of this character which will be simple and inexpensive in construction, easy to use, efficient in operation, durable in service, and a general improvement in the art.

With the above and other objects and advantages in view, the invention consists in 30 the details of construction to be hereinafter more fully described and claimed and illustrated in the accompanying drawings in which—

Figure 1 shows a longitudinal sectional 35 view through a well and my device,

Figure 2 is a cross sectional view on the line 2—2 of Figure 1, and

Figure 3 is a cross sectional view on the line 3—3 of Figure 1.

Referring more particularly to the drawings, the letter A designates a well. In carrying out my invention I provide a short section of casing 10 of a size to fit within the well and this casing is carried by tubing 40 11 of a length sufficient to reach at least to the top of the well. The lower end of this tubing 11 is secured to a tubing section 12 which is secured to the casing 10 and which is curved, as shown, so that its

45 free end will extend to and connect with the side of the casing 10. Located within this tubing 11 is a small pipe or tube 13 which may be rotated by any desired means and which carries at its lower end a flexible shaft structure 14 which extends 50 through the curved tube 12 and which car-

ries at its end a bit 15 and the purpose of this hose is to conduct water to the bit.

In the operation of the device the casing 10 is lowered to a point where a horizontal 60 cut is desired, the tubing 11 serving as a handle. When the shaft 13 is rotated the flexible shaft 14 will also be rotated and which will cause rotation of the bit 15 whereupon the teeth 16 thereof will cut away 65 the rock or other materials through which the well is drilled in the first place. The stream of water passing through the hose 17 will carry away the débris cut by the bit in the usual manner. As the horizontal hole 70 is formed the shaft 13 is fed downwardly so as to feed the bit into the material. As the hole is formed or the cut made the casing 10 may be rotated by means of the tubing 11 so as to extend the cut formed by the 75 bit 15 more or less circumferentially of the original well, as will be readily apparent.

From the foregoing description and a study of the drawings it will be apparent that I have thus provided a very simply 80 constructed and easily operated drilling device which will very efficiently perform its function of drilling horizontally below the surface of the ground and which will therefore be useful for making enlarged chambers or the like within the well or for other similar purposes.

While I have shown and described the preferred embodiment of my invention, it is of course to be understood that I reserve 90 the right to make such changes in the form, construction, and arrangement of parts as will not depart from the spirit of the invention or the scope of the subjoined claims.

Having thus described my invention, I 95 claim:

1. A device of the character described comprising a casing insertable within a well, a tube secured to said casing and serving as a handle for governing the position thereof, a hollow flexible shaft extending through said tubing, the lower end of said tubing being curved and extending to the peripheral wall of the casing, and a bit carried by 100 said flexible shaft.

2. A device of the character described comprising a casing insertable within a well, a tube secured to said casing and serving as a handle for governing the position thereof, a hollow flexible shaft extending through said tubing, the lower end of said tubing being curved and extending to the 110 peripheral wall of the casing, and a bit carried by

peripheral wall of the casing, a bit carried by said flexible shaft, and a flexible hose extending through the hollow flexible shaft and adapted to conduct water to the bit.

5. 3. A device of the character described comprising a casing insertable within a well, a tube secured to one side of said casing internally thereof, the lower end of said tube being curved and extending through the casing and terminating at the outer periphery thereof, a flexible shaft extending through said casing, and a bit carried by the free end of the flexible shaft.

10. 4. A device of the character described comprising a casing insertable within a well, a tube of considerably less diameter than

the casing secured to the inner periphery of the casing and serving as a handle for governing the position of the latter, the lower end of said tube being curved and extending 20 to the outer periphery of the casing, a flexible shaft extending through said tube and a bit carried by said flexible shaft.

5. A device of the character described comprising a casing insertable within a well, 25 a tube connected with and extending within said casing and curved to have its extremity extend to the outer periphery of the casing, a flexible shaft within said tube and a cutting bit carried by the flexible shaft.

In testimony whereof I affix my signature.

WILLIAM S. McBRIDE.
